FOREIGN PATENT DOCUMENTS

JP D1478034 * 8/2013

Primary Examiner — Brett Miller

Assistant Examiner — Rani J Abdallah

(74) Attorney, Agent, or Firm — Breiner & Breiner,
L.L.C.(57) **CLAIM**

The ornamental design for bottle, as shown and described.

DESCRIPTION

FIG. 1 is a perspective view of the bottle of the invention.
 FIG. 2 is a front view of the bottle of FIGS. 1 and 7.
 FIG. 3 is a side view of the bottle of FIGS. 1 and 7.
 FIG. 4 is a back view of the bottle of FIGS. 1 and 7.
 FIG. 5 is a top view of the bottle of FIGS. 1 and 7.
 FIG. 6 is a bottom view of the bottle of FIG. 1.
 FIG. 7 is a perspective view of another embodiment of the
 bottle of the invention; and,
 FIG. 8 is a bottom view of the bottle of FIG. 7.
 The broken lines in the figures represent portions of the
 bottle that form no part of the claimed design.

1 Claim, 7 Drawing Sheets(56)
